GAME

Walter W. Wade, Kansas City, Mo.

Application September 30, 1935, Serial No. 42,845

17 Claims. (Cl. 273—90)

This invention relates to games, wherein is incorporated structure for simulating the plays of an ordinary ball game, and the primary object is the provision of unique and novel apparatus, 5 operable by two players of the game, wherein both mechanically and electrically operated parts combine to effect the score of the game being played.

One of the primary objects of this invention is to provide a game of the aforementioned character, which has uniquely disposed ball handling elements and specially formed electrical circuits that combine with one or more of said elements so that when the game is being played, skill of the opponents will determine to a large extent the 15 winner of the game.

A yet further object of this invention is to provide a specially formed game unit that has a catapult for the ball disposed on an inclined platform at the lowest point thereof, whereby the action of 20 gravity upon the ball will always return the same to a position at the catapult.

A further object of the invention is the provision in a game structure of the foregoing type, of an inclined trough along which balls may 25 travel, which trough is provided with signal devices operable by the movement of the balls and controllable also by the position of a playing ball disposed upon the surface of the inclined platform forming a part of the game.

Minor objects, including structural details and 30 methods of playing the game will appear during the course of the following specification, referring to the accompanying drawings, wherein:

Figure 1 is a perspective view of a game made 35 in accordance with this invention.

Fig. 2 is a top plan view of the same.

Fig. 3 is an enlarged, fragmentary, vertical, cross section through the game.

Fig. 4 is an enlarged, fragmentary, sectional 40 view taken along line IV—IV of Fig. 2.

Fig. 5 is a fragmentary, sectional view taken along line V—V of Fig. 4.

Fig. 6 is a similar view, taken along line VI—VI of Fig. 4.

Fig. 7 is a fragmentary, plan view of one corner 45 of the game.

Fig. 8 is a fragmentary, detailed, sectional view through a length of the trough, illustrating one of the stops.

Fig. 9 is a top plan view of the catapult.

Fig. 10 is a fragmentary, sectional view through a portion of the platform adjacent the catapult, and,

Fig. 11 is a wiring diagram illustrating the circuit employed in the game.

It is preferred to support and house the necessary working parts and elements of this game by a table, having legs 14 that are provided with leveling devices at their lower ends, such as illustrated in Fig. 1. These devices may be in the form of a tapped plate 16, through which passes the adjustable bolt 18 that serves as a foot for each leg 14 respectively. Manipulation of these bolts 18 will permit leveling of the remaining parts of the table, which include side walls 20 and 10 the glass cover 22, carried by said walls 20 in serving therewith to complete a case illuminated by a number of electrical lamps 24, positioned beneath reflectors 26 carried by sides 20.

This aforementioned case is bottomed by a plat- 15 form 28 that has a concave rolling surface for the playing ball 30, and which is generally a flattened, inverted cone that presents a face inclined downwardly from the periphery thereof to a central zone where the catapult 32 is positioned. This 20 catapult comprises a disc of insulating material 34, having a notch 36 formed at the periphery thereof and extending inwardly to present an inclined notch as illustrated in Fig. 9. This notch is wider at the entrance thereof than the diameter of ball 30 and narrower in width at its base than the diameter of said ball 30. An upper plate of conducting material 38, which has a down-turned lip 40 entering notch 36, is insulated from lower plate 42, which has an upturned lip 44 ex- 30 tending into notch 36 at the opposite side of notch 36. Upper plate 38 is directly engaged by pintle 46 and this pintle in turn is electrically connected to wire 48. A plate 50 of copper or similar material covers a portion of the upper 35 surface of platform 28 and underlies disc 34 so that electrical connection might be made to lower plate 42 as the catapult 32 is rotated. A wire 52 joins plate 50 and a resilient tongue 54 creates a wiping contact as lower plate 42 is rotated about 40 the axis of pintle 46. Thus it will be seen that when ball 30, which is of metal, joints lips 40 and 44, a circuit will be closed.

To render the catapult 32 more realistic, a figure 56 is mounted upon disc 34 and simulates a 45 ball pitcher. The catapulting structure 32 may be spun about the axis of pintle 46 in any suitable manner, but the means for manually projecting ball 30 and spinning catapult 32 is preferable. This means includes a pulley wheel 58 mounted 50 upon the lower end of pintle 46 and another, yet larger, pulley wheel 60 carried by one of the walls 20 so that a portion thereof projects therebeyond as illustrated in Figs. 1 and 2. A belt 62 passes over pulleys 58 and 60 and the position of notch 36 55

may be manipulated so that it will receive ball 30.

The upper surface of platform 28 is preferably covered by some resilient material such as rubber, and when ball 30 is projected, it travels over this surface toward the periphery of the platform and then moves back toward catapult 32 through the action of gravity.

Ball 30 should be directed toward a striking element 64 which forms a part of a figure simulating a ball batter. This figure 66 may be spun about the axis of shaft 68 which projects through platform 28 to be engaged by pulley 70, around which belt 72 is passed. Another pulley 74, mounted upon shaft 76, journalled in bearing 78 on side 28, is in engagement with belt 72 and upon manual manipulation of pulley 74, striking element 64 spins about a vertical axis to pass over the confined area of platform 28. Obviously, when ball 30 is projected toward this striking element 64, it is likely to be engaged thereby and driven across platform 28. Stationary figures 80 may be mounted on platform 28 in positions desired and when they are engaged by ball 30, certain rules of the game are brought into force. 25 A gong 82, preferably disposed in the corner of the case diagonally opposite from striking element 64 is used to indicate "home runs" when the same is struck by ball 30.

A pit 84, formed in platform 28, receives ball 30 when it has been driven past striking element 64 and this pit is bottomed by a plate 86 that may be lifted to a level slightly above that of the adjacent portion of platform 28 when it is necessary to free ball 30 therefrom. Plate 86 is lifted 35 by merely pulling knob 88 which is in connection with rod 90 joined to one arm 92 of a bell crank lever pivotally mounted at 94. The other arm 96 of this lever engages stem 98 which projects downwardly from plate 86 and a spring 100 serves 40 to maintain these parts in the normal position. Lamps 24 have their circuit closed by a suitable switch 102 and the circuit supplying these lamps will be hereinafter traced.

Under certain conditions of play, the party operating striking element 64 will wish to introduce one of balls 104 to inclined trough 106. This trough is supported by sides 20 and extends around platform 28 thereabove. One end of trough 106 overlies the other and balls 104 may be elevated from the low and to the upper end by reciprocable elevator 108, detailed in Figs. 4, 5 and 6. This elevator 108 has an opening 110 therein to receive arm 112 that is pivotally mounted upon a shaft 114 which passes through side 55 20. When handle 116 is manipulated, elevator 108 is actuated by arm 112 and balls 104 are lifted one at a time to the upper end of trough 106. When a ball 104 is introduced into trough 106, action of gravity causes it to roll therealong toward the other and lower end.

A series of stops 118 intersect the path of travel of balls 104 and when stops 118 are in the position shown in full lines of Fig. 8, the ball is retained at that point. When stop 118 is turned so that the flattened side of shaft 120 is above ball 104, the latter is free to travel past that particular stop. These stops are located at the corners of the rectangular figure which correspond to first, second and third bases of a ball diamond.

70 Platform 28 is provided with an opening 122 at each of the four corners thereof and an electric lamp 124 is disposed beneath each of these openings respectively. As balls 104 roll along trough 106, a circuit is closed periodically to indicate that the ball is past a given portion of the

trough 106. In reality, the purpose of this structure is to visibly indicate that the ball has passed first, second or third base.

The means for closing the circuits to the various lamps 124 comprises a series of switch-like structures, each of which is the same. Each of said structures includes a contact finger 126 that is flexed by ball 104 as it passes the same. This contact finger 126 is mounted upon a short metal section 128 of the side of trough 106. This section 128 forms a part of electrical circuit and the other side 130 of trough 106 is also a part of the electrical circuit. It is notable that this side 130 is continuous. Obviously, when the switch structure at any given corner is closed, the lamp 124 beneath opening 122 at that corner will light so long as one of the balls 104 interconnects finger 126 and side 130.

The circuit which includes the switch members just described is made or broken by the presence or absence of ball 30 in notch 36 and therefore, if ball 30 reaches notch 36 before one of balls 104 passes the first spring finger 126, the rules of the game will require that the player be "out" before reaching first base. The relationship between the switches that are controlled by ball 130 and balls 104 respectively is unique and the skill of the players is brought into effect to an appreciable degree.

Reference to Fig. 11 will readily indicate one manner of providing circuits for the electrical elements of the game. Lines 132 and 134 constitute the source of electrical supply and when it is desired to illuminate platform 28, switch 102 is closed. All of lamps 24 will therefore be caused to glow because of the circuit which is closed from line 132 to wire 136, wire 138, wires 140, 142, 144, and 146, into lamps 24 by way of wires 148, 150, 152 and 154 respectively. From the four lamps 24, the circuit is completed to wire 156 through wires 158, 160, 162, and 164, respectively. Switch 102 is in wire 156 that, in turn, is joined to the other line 134 by wire 166.

The switch of which ball 30 is a part is diagrammatically illustrated at 168 and an additional switch 170 may be employed to supplement the ball closing switch. Assuming that the ball is in position as shown in Figs. 1, 2, 3 and 9, and switch 170 is closed, the various lamps 124 will be successively closed as fingers 126 are contacted by a ball 104.

Further assuming that fingers 126 are contacted by a ball, the circuit which causes lamps 124 to glow will be as follows: line 132, wire 136, wire 138, first lamp 124, contacted finger 126, wire 172, wire 173, wire 178, wire 180, switch 168, wire 182, switch 170, wire 184, wire 166 to line 134.

When spring finger 126 associated with the second lamp is closed, the circuit which supplied current to this lamp will be as follows: line 132, wire 136, wire 138, wire 140, the second lamp 124, wire 174, finger 126, wire 175, wire 173, wire 178, wire 180, closed switch 168, wire 182, closed switch 170, wire 184, wire 166 to line 134.

When the third lamp 124 is illuminated by the closing of its spring finger 126, the circuit is closed as follows: line 132, wire 136, wire 138, wire 140, wire 142, lamp 124, finger 126, wire 176, wire 178, wire 180, closed switch 168, wire 182, closed switch 170, wire 184, wire 166 to line 134.

When the fourth lamp at the lower right hand corner of Fig. 11 is illuminated by the contacting of the associated finger 126, the circuit is closed as follows: line 132, wires 136, 138, 140, 142, 144, lamp 124, spring finger 126, wire 180, closed

switch 168, wire 182, closed switch 170, wire 184, wire 166 to line 134. It is obvious from this circuit that unless switch 168 is closed by ball 130, none of lamps 124 will be caused to glow when

5 the associated spring finger 126 is contacted by one of balls 104.

The angle of inclination of trough 106 may be slightly increased directly below stops 118 and at the point of introducing balls 104 to the trough.

10 This construction will impart momentum to the balls so that they will definitely pass spring fingers 126.

The rules of the game may be varied to suit conditions and desires of the players, and while 15 a specific form of the invention has been illustrated and described, it is understood that a large number of modifications might be employed without departing from the scope of the appended claims.

20 Having thus described the invention, what is claimed as new and desired to be secured by Letters Patent is:

1. A game of the character described comprising, in combination, a conical platform; a ball; 25 a catapult rotatably mounted on the platform at the lowest point thereof for projecting the ball across the face of the platform; structure for operating the catapult; and a striking element movable over a portion of the face of said platform, said ball being returned to the catapult by action of gravity after being projected therefrom.

2. A game of the character described comprising, in combination, a platform; a ball; a catapult rotatably mounted on the platform adjacent 35 the center thereof for projecting the ball across the face of the platform; structure for operating the catapult; a pit formed by the platform at a point removed from the catapult and adapted to hold the said ball therein when the same is driven 40 thereinto by the catapult; and a device for maintaining the ball in the pit at said point and selectively lifting the ball from the pit.

3. A game of the character described comprising, in combination, a conical platform; a ball 45 on the platform; a catapult rotatably mounted on the platform adjacent the center thereof for projecting the ball across the face of the platform; structure for operating the catapult; a striking element remote from the catapult, movable over a portion of the face of said platform; and a pit formed by the platform near the striking element, said pit having a floor therein movable to and from the plane of the platform at the edge thereof.

55 4. A game of the character described comprising, in combination, a platform having a rolling surface in the form of a flattened inverted cone; a ball on the platform; a catapult having a peripheral notch formed therein rotatably mounted 60 on the platform adjacent the center thereof for projecting the ball across the face of the platform; structure for operating the catapult; a striking element remote from the catapult, movable over a portion of the face of said platform; 65 and a pit formed by the platform near the striking element, said platform being inclined downwardly from the periphery thereof to the catapult whereby the said ball will roll to the catapult by the action of gravity from any point on the 70 said platform, and said catapult may be rotated to engage the ball within the said notch.

5. A game of the character described comprising, in combination, a platform inclined downwardly from the periphery to a point adjacent 75 the center thereof; a catapult having a periph-

erial notch formed therein rotatably carried by the platform at its lowest point; and a striking element on the platform in spaced relation to the catapult.

6. A game of the character described comprising, in combination, a platform inclined downwardly from the periphery to a point adjacent the center thereof; a catapult rotatably carried by the platform at its lowest point; a striking element on the platform in spaced relation to the catapult; and independent means in connection with the catapult and striking element respectively for selectively operating the same, said means comprising pulleys rotatably mounted below the platform, projecting beyond the edges thereof and having operable connection with the said catapult and striking element respectively.

7. A game of the character described comprising, in combination, a platform inclined downwardly from the periphery to a point adjacent the center thereof; a catapult rotatably carried by the platform at its lowest point; and a striking element on the platform in spaced relation to the catapult; said catapult comprising a disc having a notch formed in the periphery thereof to receive the ball, a pintle supporting the disc, and an operating belt for rotating the pintle and disc.

8. A game of the character described comprising, in combination, a platform inclined downwardly from the periphery to a point adjacent the center thereof; a catapult rotatably carried by the platform at its lowest point; and a striking element on the platform in spaced relation to the catapult, said catapult comprising a disc 35 having a notch formed in the periphery thereof to receive the ball, a pintle supporting the disc, a pulley wheel on the pintle, another pulley wheel rotatably mounted adjacent the edge of the said platform, and a belt connecting the pulleys 40 whereby operation of the latter will rotate the disc.

9. A game of the character described comprising, in combination, a platform inclined downwardly from the periphery to a point adjacent the center thereof; a catapult rotatably carried by the platform at its lowest point; and a striking element on the platform in spaced relation to the catapult, said catapult comprising a disc having a notch formed in the periphery thereof to receive the ball, a pintle supporting the disc, and an operating belt for rotating the pintle and disc, the edges of the disc forming the notch converging as the axis of the disc is approached.

10. A game of the character described comprising, in combination, a platform inclined downwardly from the periphery to a point adjacent the center thereof; a catapult rotatably carried by the platform at its lowest point; and a striking element on the platform in spaced relation to the catapult, said catapult comprising a disc having a notch formed in the periphery thereof to receive the ball, a pintle supporting the disc, and an operating belt for rotating the pintle and disc, the edges of the disc forming the notch converging as the axis of the disc is approached, the width of the notch at the periphery of the disc being greater than the diameter of the ball and the width of said notch at the base of the notch being less than the diameter of the said ball.

11. In a game of the character described, a platform; upstanding walls around the edge of the platform; a ball on the platform; a catapult for projecting the ball across the face of the

platform; a striking element on the platform to act upon the ball when the same is met thereby; an inclined trough carried by the said walls circumscribing said platform above the same; and a ball in said trough movable by gravity from one end of the trough to the other end thereof.

12. In a game of the character described, a platform; upstanding walls around the edge of the platform; a ball on the platform; a catapult for projecting the ball across the face of the platform; a striking element on the platform to act upon the ball when the same is met thereby; an inclined trough circumscribing said platform with the ends thereof at one corner of the walls; a ball in said trough movable by gravity from one end of the trough to the other end thereof; and an elevator at said corner of the walls for lifting the ball from one end of the trough to the other end thereof.

13. In a game of the character described, a platform having a continuous circumscribing wall extending upwardly therefrom; a ball on the platform; a catapult for projecting the ball across the face of the platform; a striking element on the platform to act upon the ball when the same is met thereby; an inclined trough mounted on the wall above and circumscribing said platform; a ball in said trough movable by gravity from one end of the trough to the other end thereof; and an elevator for lifting the ball from one end of the trough to the other end thereof, said trough having a plurality of stops selectively movable to a position precluding the passage of the ball along said trough.

14. In a game of the character described, a platform; a ball on the platform; a catapult for projecting the ball across the face of the platform; a striking element on the platform to act upon the ball when the same is met thereby; an inclined trough circumscribing said platform; a ball in said trough movable by gravity from one end of the trough to the other end thereof; and a series of signal members located in the trough in the path of travel of the ball whereby to be operated thereby as the same travels from one end thereof to the other.

15. A game of the character described, comprising a platform; a ball of electrical conductive material freely movable across the face of the

platform; a rotatable disc having a peripheral notch formed therein for catapulting the said ball; a striking element on the platform remote from the disc for the purpose of intercepting the ball as it travels along certain paths of travel; and an electrical circuit including a portion of the said platform and the said notched disc, closed by the said ball when in the notch of the disc.

16. A game of the character described, comprising a platform; a ball of electrical conductive material freely movable across the face of the platform; a rotatable disc having a peripheral notch formed therein for catapulting the said ball; a striking element on the platform remote from the disc for the purpose of intercepting the ball as it travels along certain paths of travel; an electrical circuit including a portion of the said platform and the said notched disc, closed by the said ball when in the notch of the disc; an inclined trough extending around the edge of said platform; a ball in said trough movable by gravity from one end of the trough to the other end thereof; a series of electric signals each having a switch located in the said trough and operable to the closed position by the ball as it engages the same; and conductors supplying current to said switches including said disc and portion of the platform whereby said electric signals can not be actuated by the closing of their respective switches unless the said ball is in the notch of said disc to connect the said conductors.

17. A game of the character described, comprising an inverted, flattened, conical platform; a ball freely movable across the concave face of the platform; a catapult for the ball at the lowest point on the face of the platform; an electric circuit closed by the said ball when disposed within the catapult; an inclined trough associated with the platform; a ball movable along the trough; a series of electrical switches in the trough closable by the ball therein; and conductors interconnecting the said electric circuit and the said electrical switches whereby the closing of the latter is effective to complete a circuit only when the first mentioned ball is disposed within the catapult.

WALTER W. WADE.
